Primary Examiner — Lucy Lieberman*(74) Attorney, Agent, or Firm* — Morris, Manning & Martin, LLP; Christopher W. Raimund(57) **CLAIM**

The ornamental design for a watch bezel, as shown and described.

DESCRIPTION

FIG. 1 is a top plan view of a watch bezel showing my new design, the undisclosed front, rear, bottom and side views are not part of the claimed design; and,

FIG. 2 is a top plan view of the watch bezel showing my new design in an environmental structure comprising a wrist watch, the undisclosed front, rear, bottom and side views are not part of the claimed design.

The watch bezel is flat. The broken lines showing the wrist watch and the hour and minute hands of the wristwatch in FIG. 2 are for the purpose of illustrating environmental structure only and form no part of the claimed design.
